UNITED STATES PATENT OFFICE.

WARD MELVILLE, OF OLD FIELD, AND JAMES CAMERON MACKENZIE, JR., OF NEW YORK, N. Y., ASSIGNORS TO MELVILLE SHOE CORPORATION, A CORPORATION OF NEW YORK.

DESIGN FOR A STORE FRONT.

Application filed April 13, 1929. Serial No. 30,892. Term of patent 14 years.

To all whom it may concern:

Be it known that we, WARD MELVILLE and JAMES CAMERON MACKENZIE, Jr., citizens of the United States, residing, respectively, at Old Field, county of Suffolk, State of New York, and the city, county, and State of New York, have invented a new, original, and ornamental Design for Store Front, of which the following is a specification, reference being had to the accompanying drawing, forming a part hereof.

In the drawings,

We claim:

The ornamental design for a store front, as shown.

WARD MELVILLE.
